UNITED STATES PATENT OFFICE.

WARREN B. REED AND WALTER HEPLER, OF MORGAN CITY, LOUISIANA.

DRILLING APPARATUS.

Application filed February 27, 1922. Serial No. 539,566.

To all whom it may concern:

Be it known that we, WARREN B. REED and WALTER HEPLER, both citizens of the United States, both residing at Morgan City, in the parish of St. Mary and State of Louisiana, have invented certain new and useful Improvements in Drilling Apparatus; and we do hereby declare the following to be a full, clear, and exact description 10 of the invention, such as will enable others skilled in the art to which it appertains to make and use the same.

This invention relates to oil drilling apparatus, and has for its object to provide a 15 means of this character which will be simple in construction, comparatively inexpensive to manufacture, and more efficient in operation than those heretofore proposed.

With these and other objects in view the 20 invention consists in the novel details of construction and combinations of parts more fully hereinafter disclosed and particularly pointed out in the claims.

Referring to the accompanying drawings 25 forming a part of this specification, in which like numerals designate like parts in all the views:

Figure 1 is a diagrammatic vertical sectional view of an apparatus made in accordance with this invention;

Figure 2 is a sectional view taken on the line 2—2 of Figure 1, looking in the direction of the arrows;

Figure 3 is a bottom plan view partially 35 in section and with certain parts omitted, of the apparatus shown in Figure 1;

Figure 4 is an enlarged detail sectional view of the lower cutting portion of the apparatus;

Figure 5 is a sectional view taken on the line 5—5 of Figure 4, looking in the direction of the arrows; and

Figure 6 is a sectional view taken on the line 6—6 of Figure 4, looking in the direction of the arrows.

This invention is an improvement over the prior Patent #1,378,056, dated May 17, 1921, to W. B. Reed and W. Hepler.

As is well known, in the drilling of oil 50 and other wells, it is often desirable to obtain samples or "cores" of the various strata through which the drill passes and in many instances it is also desirable to know the kind of formation lying just ahead of the hole which is being bored to size, in which cases a core such as would be produced with

a diamond drill in formations that would permit of its use would be of extreme value to the driller.

In the rotary system of drilling wells, 60 the samples of the cuttings of the "fish tail" or other type of bit are brought to the surface by means of water which is pumped down through the hollow drill stem, through the bit at the bottom of the hole and then back up outside the drill stem. In our previous patent, however, above referred to, these core samples were brought up intact without the aid of water and in this particular invention these said core samples 70 are likewise brought up intact and free from water, all as will be disclosed herein-after.

Referring to the drawings, 1 indicates the drill stem screwed into the upper head member 2 which receives at its lower end by means of the screw threads 3 the drill pipe 4 which is screw threaded at its lower end as at 5 and has screwed thereto the cutter head member 6. Into the extreme lower 75 edge of the member 6 are fitted the individual bits or cutters 7 each provided with an extension 8, see Figure 4, fitting in a recess 9 in the member 6; and 10 represents set screws carried by said cutter member 6 which take against the extensions 8, and thus hold the cutters 7 in place, all as will be clear from Figures 1, 3 and 4. Located inside the lower edge of the cutter head 6 and screw threaded thereto as at 11 is the 80 fish tail cutter or bit 12 provided with a solid plug portion 13 at its upper end. Rigid with said upper end or plug portion 13 is the guide sleeve 14 adapted to move up and down inside the core tube 15 which 85 is closed at its upper end by the plug 16 having the orifice 17 in which is screw threaded the short pipe 18 entering the inverted chamber 19 with which the upper 90 head member 2 is provided. At the extreme lower end of the drill pipe 4 and inside the cutter head member 6 is disposed the removable spider member or ring 20, carrying at its lower end the segments or 95 valve members 21 hinged as at 22 to said ring member 20. Said valve members are adapted to fold upwardly as indicated in dotted lines in Figure 4, and in full lines in Figure 1. The drill stem 1 is hollow as shown, and the upper head member 2 is 100 provided with a plurality of passages 25 through which water may pass from the

drill stem 1 and may enter the space 26 above the plug 16 and flow down through the space 27 between the core tube 15 and the outer drill pipe 4, all as will be clear from Figures 1 and 4.

When the water reaches the extreme lower end of the pipe 4, it enters the passages 28 with which the ring member or spider 20 is provided, and from said passages 28 it 10 enters the passages 29 with which the cutter head is provided. These passages 29, as best shown in Figures 1 and 3, terminate on the extreme lower edge of the cutter member 6, and between the individual bits 7, so that 15 the mud fluid or water readily reaches the extreme lower cutting points 30 of the bit 7 and thus prevents an undue heating of said bits which has heretofore given a great deal of trouble in drills of this character.

20 After leaving the passages 29 the said water or mud fluid passes up outside the drill pipe 4 as indicated by the arrows 31, and is pumped out of the well in the usual manner. As the drill is rotated, the fish 25 tail bit 12 unscrews from the screw threads 11 carried by the short pipe section 33 and together with the guide sleeve 14 passes up on the interior of the core tube 15. The short pipe or tube section 33 extends down 30 below the lower edge of the cutter member 6 a considerable distance, as is illustrated in Figure 1, and it serves the important function of preventing the water which exits from the passages 29 from washing out the 35 core material which is forced up inside said tube 33 as the cutters 7 rotate.

The operation of this new drilling construction will be clear from the foregoing, but may be briefly summarized as follows:

40 Upon rotating the drill pipe 1 and cutters 7, the fish tail member 12 will unscrew from the sleeve 33 and together with the integral guide tube 14 will be pushed up into the core tube 15. The cutters 7 continuing to 45 rotate will force the cut material into the core barrel until the guide sleeve and member 13 reach the top of said barrel if the core is of a sufficient length. This construction whereby the core barrel is initially 50 closed by member 13 constitutes an important feature of this invention, because it maintains, until the member 13 rises a closed core barrel that does not gather scrapings from the side of the hole and therefore the 55 core obtained by this apparatus is not mixed with material from miscellaneous depths as is found to be the case in previous constructions.

In other words, it will be clear that the 60 members 12, 13 and 14, constituting a single rigid structure which we call the plug bit, effectually closes the core barrel 15 against the entrance of extraneous material before the core is cut; and the unscrewing of this 65 said structure or plug bit from the threads

11 opens the core barrel to receive the cut core material after the cutter head is in operation, so there is no way by which the core that is brought to the surface can be contaminated with extraneous matter.

70

The results are with this invention that one is enabled to take an uncontaminated core at the exact location desired and thus obtain data which can be absolutely relied upon.

75

Another important feature of this invention resides in the construction by which the cutter bits 7 can be readily removed, sharpened, and replaced and at a comparatively small cost. That is to say, by providing these removable bits 7 we eliminate the large expense incident to the use of a rotary shoe with fixed cutters which has to be thrown away as soon as its cutting points are dulled.

80

The water which flows down through the hollow pipe 1 passes through the channels 25, 27, 28, and 29 to the extreme points 30 of the said bits 7, and then up outside the pipe 4 as indicated by the arrows 31, so that all overheating of the cutters 7 is prevented. This constitutes another important feature of the invention, because in the prior drills the getting of mud and water to the very edge of the bit is not accomplished. In such prior devices after boring the core 90 for a short time the fit between the rock and other material and the cutting member is so tight that the water does not penetrate to the cutting edge of the tool at all, and so great is the heat generated that burnt cores 95 result.

95

In fact, it is a common practice to have clay or shale cores fused into the rock and thus destroy the evidence desired or producing false evidence. It has even been observed that the iron barrels carrying the cutting edges have been fused with the clays of the formation owing to the lack of water for cooling said edges.

100

In this invention, on the other hand, actual experience has shown that the placing of water under pressure at the extreme cutting edges 30 as disclosed above, not only facilitates the cutting of the rock but it 110 positively eliminates all burning of the cores.

115

Another feature of importance in this invention resides in the fact that the water and mud is effectually prevented from reaching the core in the core barrel 15. In its downward passage it is excluded from said core barrel by the plugs 16 and pipe 18, while in its upward passage it passes outside the drill pipe 4 and thus is the mud and water from the drill stem or pipe prevented from coming in contact with the core material at all times.

120

The short tube 33, as stated above, constitutes still another important feature of 125

130

the invention, in that it prevents the water coming from the passages 29 from jetting against the core material and thus eliminates the washing of the cores.

5 Accordingly, it results that even in soft material, a core of full size can be cut and carried up into the tube without contamination or serious loss of the material. In all cases, it is found when this tube 33 is used, 10 that the central portion of the core remains in the identical form in which it lies in the stratum and thus furnishes the valuable data which is sought.

Still another important feature of this invention resides in the removable ring or spider 20 into which a core tube 15 fits as shown. This spider is provided with the passages 28 for the water and also carries the four hinged segments 21 that drop down 0 into the full line position shown in Figure 4 and thus prevent the core material from slipping out of the core tube when the drill is raised. It is found in practice that these segments 21 act in various ways with different materials.

That is to say, when a rock core is formed, they lie against it, and engage in the uneven edges of the core, thus preventing slippage. In a core of clay, such, for example, as that 30 known as "gumbo" or shale, they do not ordinarily function because this type of material almost invariably packs in the core barrel and does not tend to escape from said barrel. Accordingly, such clay material 35 usually seals the segments in a vertical position.

In a sand core, on the other hand, the segments are found to invariably drop into the full line position shown and thus prevent 40 the sand from escaping. It has been found in practice that if a single segment drops it will hold the core. We have not lost a single core after having tried these segments.

45 When the core tool is first introduced into the hole the core tube 15 fills with water or drilling fluid through the holes 36, see Figures 1 and 2, but as the core material pushes upwardly the guide tube 14 and plug 13 50 from the bottom, this water is replaced by said plug and escapes through said passages 36 into the regular channel.

The sliding fits between the parts 18 and 55 19, and between the core barrel 15 and the sleeve 14 and its associated parts are so proportioned as to accomplish this result.

It will therefore be seen that this particular construction of water head constitutes a valuable improvement over prior constructions in that we do away entirely with the back pressure valves at the top of the core barrels that have been heretofore found necessary. We therefore avoid the objection to 60 these back pressure valves due to the pump pressure keeping them closed. These pump

pressures in the prior constructions would often close these valves with such a force that cores of loose material became disintegrated by water in the core barrels that could not exert pressures, as the cores would 70 rise, that would be sufficient to overcome the said pump pressures on said back pressure valves; and the loose core materials were, as a result of these objections, often carried away by the water, upon the outside of the water head, and thus would 75 valuable data be lost. With the construction of water head disclosed above, however, such an objection is avoided.

The spider member 20 is made removable 80 in order to facilitate the construction for it has been found difficult to otherwise insert the dropped segments 21, as well as to drill passages 28 through said spider.

In addition to this, unless the spider 20 85 were made removable it would be difficult to drill the water passages 29 through the cutter head. The sleeve or short tube 33 is made removable because its thread 11 is subject to wear and the sleeve can be replaced at small expense when it is removable.

It is obvious that those skilled in the art may vary the details of construction as well as the arrangement of parts without departing from the spirit of the invention, and therefore we do not wish to be limited to the above disclosure except as may be required by the claims.

What we claim is:

1. In an apparatus of the class described the combination of an outer drill pipe; a core tube located inside said pipe; a guide tube inside said core tube; and a plug member associated with said guide tube and 105 adapted to be pushed up into said core tube by the core material, substantially as described.

2. In an apparatus of the class described, the combination of an outer drill pipe; a core tube located inside said pipe; means for closing the upper end of said core tube; a guide tube inside said core tube; a plug member associated with said guide tube and adapted to be pushed up into said core tube 110 by the core material; and means to hold said plug member below the bottom of said core tube until after the drill pipe has been rotated, substantially as described.

3. In a drill the combination of a cutter head; a removable cutter bit attached to said head; a plug member; a guide tube associated with said member; means to detachably attach said plug member to said cutter head; and a core tube into which said guide tube and plug member are adapted to be forced by the core material, substantially as 125 described.

4. In a drill the combination of a cutter head; a removable cutter bit attached to 130

5. In a core drill apparatus, the combination of a head having cutters to cut the material at the bottom of the hole, said apparatus having a chamber into which a core of the material may rise, and a closure normally closing the entrance to said chamber as the apparatus is being lowered into the well, said closure being dislodged from its normal position as a consequence of the drill being operated in the well, to rise in said chamber, followed by the core of the material.
6. In a core drill apparatus, the combination of a head having cutters to cut the material at the bottom of the hole, said apparatus having a chamber into which a core of the material may rise, a closure for the lower end of said chamber having screw threaded connection therewith, and released from said threads due to contact with the bottom of the hole and the rotation of the apparatus,
7. In a core drill apparatus, the combination of a head having cutters and a central bore to receive a core of the material being cut, a closure for initially closing the lower end of said bore to prevent material from entering the same, and means whereby said closure is dislodged from its closing position when the drill is rotated, said apparatus having a chamber into which the said closure and core will relatively rise as the cutting at the bottom of the hole proceeds, substantially as described.
8. In a core drill apparatus, the combination of a head having cutters to cut the material at the bottom of the hole, said apparatus having a chamber into which a core of the material may rise, and a closure normally closing the entrance to said chamber as the apparatus is being lowered into the well, said closure being dislodged from its normal position as a consequence of the drill being operated in the well, to rise in said chamber, followed by the core of the material.
9. In a core drill apparatus, the combination of a head having cutters to cut the material at the bottom of the hole, said apparatus having a chamber into which a core of the material may rise, a closure for the lower end of said chamber having screw threaded connection therewith, and released from said threads due to contact with the bottom of the hole and the rotation of the apparatus,
10. In combination in a core drill, a head having cutters to cut the material at the bottom of the well, said apparatus having a chamber to receive a core of the material, a closure for the lower end of the chamber screw threaded into connection therewith, said closure having an extension to engage the bottom of the hole and prevent the rotation of the closure in unison with the rotation of the cutter head, whereby said closure will be disconnected from the wall of the chamber to rise therein, followed by the core of the material, substantially as described.
11. In combination in a core drill, a head having cutters to cut the material at the bottom of the well, said apparatus having a chamber to receive a core of the material, a closure for the lower end of the chamber screw threaded into connection therewith, said closure having an extension to engage the bottom of the hole and prevent the rotation of the closure in unison with the rotation of the cutter head, whereby said closure will be disconnected from the wall of the chamber to rise therein, followed by the core of the material, said closure carrying a fish-tail bit, substantially as described.
12. In a core drill apparatus, the combination of a head having cutters to cut the material at the bottom of the hole, said apparatus having a chamber into which a core of the material may rise, and a closure normally closing the entrance to said chamber as the apparatus is being lowered into the well, said closure being dislodged from its normal position as a consequence of the drill being operated in the well, to rise in said chamber, followed by the core of the material, said core receiving chamber being vented at its upper end to the exterior of the apparatus.
13. In a core drill apparatus, the combination of a drill stem through which flushing water is directed downwardly, a head having cutters, a core tube within the apparatus having its upper end closed against entrance of water from the drill stem, said apparatus having passages for directing flushing water to the cutters, and a closure for the lower end of the apparatus to initially prevent material from entering the core tube until the apparatus is operated in the well, said closure then being automatically dislodged so that the core material may rise in the core tube, substantially as described.
14. In combination in a core drill, a member having a core receiving chamber, cutters, a plug for closing the lower end of the apparatus to prevent the entrance of material until after the apparatus begins to cut at the bottom of the well, said plug then

being automatically dislodged to rise into said chamber to be followed by the core, members pivoted in the apparatus to engage the core, said plug having an upward extension to engage said pivoted members to hold them normally in position, extending upwardly from their pivots.

15. In combination in a core drill, a member having a core receiving chamber, cutters, a plug for closing the lower end of the apparatus to prevent the entrance of material until after the apparatus begins to cut at the bottom of the well, said plug then being automatically dislodged to rise into 10 said chamber to be followed by the core, members pivoted in the apparatus to engage the core, said plug having an upward extension to engage said pivoted members to hold them normally in position, extending upwardly from their pivots, said extension being in the form of a sleeve substantially as described.

16. In combination in a core drill, a head having cutters at its edge, means for shielding the core of material from the flushing water projecting down from the head and out beyond which the exterior cutting edges lie, said head having passages for flushing fluid with their outlets outside of said shield 25 means and above the lower edge of same, said apparatus having a chamber to receive the core and a plug bit initially closing the lower entrance opening to said chamber, and projecting below the shield means, said plug 30 being dislodged automatically by contact with the bottom of the hole, to rise into the said chamber to be followed by the core, when the apparatus is operated, substantially 35 as described.

40. 17. In combination in a core drill, a cutter, a core tube, a closure for the lower end of the core tube, said closure being automatically dislodged when the apparatus is rotated to rise into the tube followed by the core, 45 retainers held in retracted position initially by a part of the closure, said retainers automatically engaging the core to retain it in the tube when the closure rises to a position above the retainers, substantially as de- 50 scribed.

18. In a core drill, the combination of an outer casing or tube, an inner core receiving

tube with a space between said tubes for the flow of flushing fluid, a closure for the lower end of the core tube, with means 55 whereby said closure is automatically dislodged to rise into the core tube when pressed up therein by the core of material, a hollow cutter head surrounding the core tube and having cutters mounted thereon, 60 and means to convey flushing fluid to the cutter edges, substantially as described.

19. In combination in a core drill, a rotary drill bit having cutters and having a central bore to receive the core, a drill stem connected to the bit, passages for directing flushing fluid to the cutters, said bit having shield means surrounding the central bore to prevent flushing water from acting on the core material, the outlet of said flushing 70 fluid passages being above the lower edges of the cutters and the cutters having laterally open spaces between them for the flow of the flushing fluid outwardly to the substantially vertical cutting edges of the cutters, 75 said shield means comprising a ring-shaped member having openings through which the cutters extend to present their inner cutting edges within said shield, substantially as described.

20. In combination in a core drill, a rotary drill bit having cutters and having a central bore to receive the core, a drill stem connected to the bit, passages for directing flushing fluid to the cutters, said bit having 80 shield means surrounding the central bore to prevent flushing fluid from acting on the core material, said cutters extending through said shield means to present cutting edges inwardly and outwardly in respect thereto. 85

21. In a core drill, the combination of a hollow bit carrying removable cutters, a chamber to receive the core, a ring removably seated in the core bit and surrounding the bore thereof, said ring having slots extending from its lower edge upwardly and terminating short of the top of said ring, 90 said removable cutters extending through said slots and preventing dislodgement of said ring.

In testimony whereof we affix our signatures.

WARREN B. REED.
WALTER HEPLER.
